WIRE BOUND CRATE

Application filed March 22, 1930. Serial No. 438,153.

This invention relates to crates or baskets of the "wire bound" type and is more particularly concerned with a crate of rectangular cross section permitting the use of light 5 stave stock while providing maximum rigidity and durability and arranged for economical manufacture.

Crates or baskets of this type, as heretofore constructed, have lacked rigidity and 10 durability and have been subject to distortion and to bulging and breakage through internal load pressure.

In accordance with the present invention as one feature thereof I have provided an 15 adequately braced top and bottom formation of particularly advantageous construction and side walls of light stave stock made rigid and braced by inward tensioning applied through an external bracing and tensioning 20 reinforcement.

The invention includes as a further feature, a top construction embodying continuous inner and outer batten strips having 25 their faces scored at the corners of the top of the crate and bent at right angles to the rectangular form of the crate with the tops of the staves forming the side walls of the crate enclosed between the inner and outer batten strips and secured thereto by suitable 30 inserted fastenings and with an external binder of wire or metal strapping applied to and encircling the outer batten strip and fastened thereto and preferably also to the staves and inner batten strip, thereby providing a strong, braced top edge to the crate 35 resisting deformation by handling and by internal and external pressures. This top edge is further braced and made rigid by inward tensioning applied through the tensioning of the stave side walls as heretofore 40 stated.

A further feature of the invention resides in a bottom construction for the crate comprising separate cleats engaging and extending 45 around the inner faces of the staves at the bottom and nailed or otherwise fastened thereto, with their top edges supporting a plurality of relatively thin staves forming the bottom, and with an external bracing wire 50 or strap encircling the outer faces of the

staves at their bottom and nailed or otherwise fastened thereto.

These and other features of the invention will be more clearly apparent from the following detailed description which is to be 55 read in conjunction with the accompanying drawing forming part thereof and in which

Figure 1 is a top plan view of a crate constructed in accordance with the present invention. 60

Figure 2 is a front elevation of the crate as shown in Figure 1.

Figure 3 is a fragmentary transverse vertical section on an enlarged scale through the 65 crate shown in Figures 1 and 2, and

Figure 4 is a perspective detail on an enlarged scale of one corner of the crate at the top edge showing the manner of joining the ends of the cleats and binder wire. 70

The crate of the present invention is rectangular in cross section and preferably tapered in form to permit nesting and conservation of space in storing and shipping and is composed of a shell of staves 1 which in the tapered form of the crate shown in Figure 2 may be advantageously of tapered form arranged with the staves at each side of the rectangle appropriately disposed as by the reversal of an intermediate stave as shown in Figure 2 to provide the outer edges of the sides formed thereby with the appropriate downward taper. The upper and lower ends of the rectangular shell of staves are braced upon their internal faces by cleats extending continuously around their internal faces and by external binders opposed thereto and engaging the external faces of the staves to the top and bottom. These external binders are fastened by appropriate means to the staves 75 and to the internal cleats. 80

As shown in Figures 1 and 3 the bottom of the crate is formed by separate butting cleats 2 engaging and extending continuously around the inside faces of the staves 1 at their bottom and by an external binder which 85 may be in the form of a wire 3, or alternately by strapping, drawn tightly around and fastened as by staples 4 to the staves 1 at their bottom edge and to the cleats 2 engaging the inner faces of these bottom edges. Obvi- 90

ously the cleats 2 are rigidly joined to each other at their abutting ends in a suitable manner to form rigid corners as by dove-tailing or other commonly used methods. The external binder 3, if a wire is used, has its opposite ends drawn tightly together, overlapped and spliced as shown in Figure 2 similarly to the overlapping and splicing of the external binder wire applied to the top edge of the 10 crate as illustrated in Figure 4 and herein-after described. A bottom, proper, for the crate is provided by, preferably, a series of thin boards or slats 5 having their opposite ends resting upon the top faces of opposed 15 cleats 2 with the sides of the end slats of the bottom resting upon the top faces of the opposite pairs of cleats 2 as shown in Figure 1. Obviously instead of a series of slats 5 a single piece of material may be employed.

20 The top edges of the staves 1 forming the shell are braced against deformation by a continuous cleat 6 of thin wood scored at the points representing the corners of the inside 25 of the top indicated at 7 (Fig. 4), and bent on the line of scoring to form a continuous rectangular strip conforming to and engaging the inside faces of the staves 1 at their top edges. Preferably the stave strip is of a 30 length in excess of the internal perimeter of the crate top so that its ends will overlap as shown at 8 in Figure 1 to provide means for fastening the stave strip together in its stave 35 engaging position. Opposed to the continuous stave strip 6 and overlying the outer faces of the staves 1 at their top edges is a similar 40 continuous stave strip 9 having its inside face scored as at 10 (Fig. 4) at points representing the external corners of the top edges of the crate and bent on the lines of scoring to engage the outer face of the staves at their top edges and enclose the top edges of the staves between these inner and outer cleat strips. 45 With the rectangular form of the top edge maintained by the bracing afforded by the enclosing cleats which as will be seen are fastened to the staves in tight conformation therewith, the outer stave strip 9 is drawn to tight enclosing engagement with the staves 1 by means of a continuous external binder 50 which as shown is composed of wire 11 but which may be in the form of other strapping. The ends of the binder 11 are drawn together and overlapped preferably at a corner 55 of the crate as shown in Figure 4 and are spliced as shown with the wire binder 11 tightly engaging the outer cleat strip 9 and holding the same tightly against the outer faces of the staves 1. Appropriately the outer binder 11 may be fixed to the outer cleat 60 strip and to the staves and inner cleat strip by staple fasteners 12 passing through the inner and outer cleat strips and through the intervening staves and clinched at their inner ends as shown in Figure 3 to join these parts 65 together. By using continuous cleat strips

scored for bending at right angles to form corners, a substantial manufacturing economy is afforded since the crate may be made and completely assembled in one operation.

Crates as previously constructed have been subject, even with their top and bottom ends well braced, to deformation, outward bulging and breakage through pressure of their load contents when the shell or side walls of the crate are formed of flexible staves due to the relatively weak structural strength of these side walls. I have substantially increased the strength of the stave side walls by tensioning them inwardly and holding them under inward tensing pressure by means of an external binder wire 13 (Fig. 2) encircling the external sides of the staves 1 intermediate their top and bottom edges, the ends of the binder wire 13 being drawn together and overlapped preferably at a corner of the shell as suggested in Figure 4, and spliced and fastened to the staves of the shell with the binder wire 13 applying and maintaining inward tensioning of the staves with the tensioning pressure at a maximum at the corners. With the looped ends of the binder wire 13, one of which is shown at 14 (Fig. 2) stapled to the staves 1 and with the staples or other fasteners holding the wire 13 to the staves 1 at intervals along its intervening length the inward tension thus applied will be maintained and the side walls and corners of the crate will be made substantially more rigid and offer a substantially greater amount of resistance to deformation through outward pressure than has hitherto been possible with prior constructions. With this inward tensioning of the side walls which as suggested in Figures 1, 2 and 3, will result in producing a slight convexity of the side walls inwardly, the corners of the crate structure will be substantially strengthened and the top of the crate through inward tension applied through the top ends of the staves will also be slightly bowed inwardly thereby increasing its strength and resistance to breakage at this point. This inward bowing of the rim structure puts the corners under pressure and thus adds reinforcement to places which take much of the knocks and bumps in the handling of the crate. Appropriate handles may be secured to the reinforced top edge of the crate, such for example, as the wire bail handles 15 shown in Figures 1 and 2. The crate while preferably made tapering in form because of the advantages of nesting and saving in storage space may obviously be of uniform cross section at the top and bottom securing the same benefit of inwardly tensioned side walls as when made of tapering form. The particular structural details of the crate while representing a preferred embodiment of the invention are intended as illustrative rather than restrictive and are subject to modifications and

changes adapting the invention to different conditions of manufacture and use in consonance with the spirit of the invention and the scope of the appended claims. In addition to reinforcing the corners of the crate the foregoing bowing of the rim structure has the advantage of bringing out an absolutely compact nesting of a number of filled crates in the following manner: Assume a number of the crates to be filled with fruit or the like and stood on a floor. The tendency of the inward bowing of the rim structure is to resist outward bulging, but eventually there may be a yielding of the rim structure due, perhaps, to a slight softening of the wood or perhaps to the perpetual joggling of the contents during transit.

Looking down on the foregoing numbers of crates one may see the outward bulging or yielding of one side of the rim structure of a given crate as being stopped by a corresponding yielding or outward bulging of the side of the rim structure of an adjoining crate. The same effect may be noted between crates in all horizontal directions, so that where originally there were elongated spaces between rim structures such spaces have now become filled by the slight outward yielding or bulging of the rim structures, making an absolutely compact formation between the rim structures of all of the crates. The effect can be visualized by considering all of the crates as having expanded, so to speak, into a unitary and compact mass. This condition prevents any shifting of the load whatsoever, so that there is no danger of damage to the contents by bruising, etc., in transit.

I claim:—

1. A crate comprising a shell of substantially rectangular cross section composed of staves and including a bottom, cleats and binders secured to the upper and lower ends of the staves, and a continuous external binder attached to the shell intermediate of its upper and lower ends exercising a contracting pressure to bow the sides of the shell inwardly but being permissibly yieldable outwardly.

2. A crate comprising a polygonal shell of staves, internal cleats extending continuously around and engaging the inner faces of the staves at their lower ends, a crate bottom affixed to said cleats, a continuous external binder applied to the outer faces of said staves at their lower ends in opposition to said cleats, a continuous inner cleat strip scored and bent at the corners of the top of said shell and engaging and extending continuously around its inner face at its upper end, a cooperating similarly scored outer cleat strip engaging and attached to the outer face of said shell and to the inner cleat strip, a binder encircling and secured to said outer cleat strip, and a continuous intermediate binder encircling said shell between its upper

and lower ends and fixed thereto under contracted tension producing and maintaining inward bowing tension of the sides of the shell and said cleat strips.

3. A crate comprising a shell of staves of substantially rectangular cross section, a binder wire applied to the shell substantially medially of its ends, said binder wire being under tension and therefore bowing the staves inwardly, a rigid bottom structure mounted in one end of the shell, and a rim structure at the remaining free and top end of the shell, the inward bowing of the staves being imparted to said rim structure to bow said rim structure inwardly and thereby put the corners under pressure to establish a reinforced corner structure.

4. A crate to compose a unit of massed crates, said crate comprising a shell and staves of substantially rectangular cross section, a bottom for the shell and a rim structure the corners of which are abuttable by the rim structures of adjoining crates, and a binder wire contracting the shell into inwardly bowed form and initially bowing the rim structure inwardly, said bowing tending to resist outward bulging due to the contents of the crate, but being permissibly yieldable until the rim structures of all adjacent crates in one plane meet to form a solid mass of crates.
